UNITED STATES PATENT OFFICE.

CHARLES OWENS, OF CHATTANOOGA, TENNESSEE.

FEED-CONTROLLING MECHANISM FOR MAGAZINES AND THE LIKE.

No. 890,089.

Specification of Letters Patent.

Patented June 9, 1908.

Application filed March 14, 1906, Serial No. 306,063. Renewed October 30, 1907. Serial No. 399,854.

To all whom it may concern:

Be it known that I, CHARLES OWENS, a citizen of the United States, residing at Chattanooga, Tennessee, have invented certain new and useful Improvements in Feed-Controlling Mechanism for Magazines and the Like, of which the following is a specification.

My invention relates to mechanism for controlling and regulating the feeding of magazines, newspapers, plates or like articles to printing mechanism or the like wherein it is desired to feed the articles forward one at a time.

The invention consists in the features and combination and arrangement of parts herein described and particularly pointed out in the claims.

In the accompanying drawings,—Figure 1 is a side view of a machine embodying my invention. Fig. 2 is a rear elevation of parts shown in Fig. 1, some of the parts however being omitted. Fig. 3 is a detail view of an adjustable stop.

The articles to be fed forward are indicated at 1 in a hopper or frame 2 resting with their rear ends upon an adjustable bar 3 and the forward end of the pile of articles rests upon the feed drums 4 which have peripheral supporting surfaces 5 for the said articles, and flanges 6 at the outer side of the said peripheral supporting surfaces. These feed drums are carried by a shaft 7 which is rotated in any suitable manner and they carry fingers 8 adapted to enter between the leaves of the magazine, and thus feed the same forward in a manner similar to that shown in an application for Letters Patent of the United States filed by Alexander Lyle, Jan. 30, 1905, #243385.

Above the feed drums and over the peripheral supporting surfaces thereof, controlling ratchets 9 are arranged, one for each of the drums. These ratchet wheels are arranged with a slight space between their lower peripheries and the peripheral supporting surfaces of the drums, and between these ratchets and drums the magazines or other articles are fed. The magazines in the pile rest with their forward edges against the teeth of the ratchet, as shown in Fig. 1. Associated with the ratchet wheels are releasers 10 consisting of plates reaching down on each side of each of the ratchets from sleeves 11, which are adjustably connected by a set screw and slot connection at 12 with

the frame work of the machine. The central portions of these releasing plates are journaled upon the shaft 13 which carries the ratchets and the lower edges of the releaser plates are curved concentric with the ratchet wheels and these curved edges extend in the horizontal plane or slightly beyond the horizontal plane of the teeth. The ratchet wheels are driven step by step by pawls 14 attached to the arms 15, journaled on the shaft 13, the said pawl arms being driven by the link 16 from the crank disk 17 on the drum shaft. The connection between the link 16 and crank disk 17 is adjustable as shown at 18, the said crank disk having a slot 19 extending across it in which the said connection may be set.

The operation of the machine is as follows: The magazines having been placed in the hopper 2 and the feed drums 5 having been set in rotation, the feed blades of the said drums enter between the leaves of the lowermost magazine and draw it from beneath the pile. The forward edges of the magazines are brought against the teeth of the ratchet wheels and thus all of the magazines in the hopper, or at least those at the lower portion of the pile are brought into positive engagement with the teeth of the ratchet wheel except those which are below the point *x* of the releaser plates, these latter magazines being loose or not engaged by the said ratchet teeth and being free to be fed forward by the fingers of the feed drums between the lower edges of the releaser plates and the peripheral supporting surfaces of the drums.

It will be seen that the number of magazines which are loose or disengaged from the ratchet teeth depends upon the position of the releaser plates in their relation to the bite between themselves and the peripheral supporting surfaces of the feed drums, and as above stated the releasers are adjustable so that more or less of the lowermost magazines will be left free to be fed forward. As the feed drums revolve they operate the ratchets through the connections described in the direction of the arrow, the throw of the ratchet or its step by step movement being determined by the position of the fulcrum or connection 18 on the disk 17. The parts may be so adjusted that the two or three lowermost magazines will lie loosely on the peripheral supporting surfaces of the drums and when engaged by the feed blades or fingers will pass easily from beneath the pile. The ratchet

wheels are revolved at such speed as to keep pace with the diminishing of the pile, namely, about two teeth for each revolution of the feed drums. The forward edge of the pile of 5 magazines can always be held up by the teeth on the ratchet wheels.

From the above it will be seen that the important feature of my invention is the control of the weight of the pile of magazines by 10 the engagement of said magazines with the teeth of the ratchets preventing more than one from feeding at a time by the movement of the ratchet past the point at which the ratchet and drum surface most nearly approach each other.

An adjustable stop is provided at 18' on the inner side of each releaser and this can be so adjusted as to positively separate the 20 magazines lying at the bite of the ratchet and drum and prevent more than one from feeding. The arrangement can be used with any suitable form of feed.

I claim as my invention:

1. In combination, a feed drum arranged 25 to support the forward portion of the magazines, means carried by the feed drum for engaging the magazines, controlling means engaging the pile of magazines and arranged opposite the feed drum with a space between 30 for the passage of the magazines, said controlling means consisting of a wheel having teeth or projections thereon and adjustable releaser means to cover more or less of said teeth or projections and shield them from the 35 pile of magazines, substantially as described.

2. In combination, a feed drum having means to engage the magazines, a controlling ratchet arranged opposite the feed drum, means for rotating the ratchet step by step, 40 and releaser means to shield more or less of the ratchet teeth in respect to the pile of magazines, substantially as described.

3. In combination, the feed drum, carrying means to engage the magazine, a ratchet 45 wheel arranged opposite the drum with a space between for the passage of the magazines, said ratchet wheel having its teeth adapted to obstruct the forward movement 50 of the magazines, means engaging the said

ratchet teeth for operating the ratchet, and releaser means to cover more or less of the ratchet teeth in respect to the pile of magazines, substantially as described.

4. In combination, the feed drum, carrying means to engage the magazine, a ratchet wheel arranged opposite the drum with a space between for the passage of the magazines, said ratchet wheel having its teeth adapted to obstruct the forward movement of the magazines, means engaging the said 60 ratchet teeth for operating the ratchet, and releaser means to cover more or less of the ratchet teeth in respect to the pile of magazines, said releaser means being adjustable about the axis of the ratchet, substantially 65 as described.

5. In combination, a feed drum, an adjustable support for the rear portion of the pile of 70 magazines, a ratchet wheel arranged opposite the feed drum and between which and the feed drum the magazines pass, means for operating the ratchet and a releaser adapted to shield more or less of the ratchet teeth in 75 respect to the pile of magazines, substantially as described.

6. In combination with the feed drum, a rotary device opposite the peripheral surface of the feed drum with its periphery adjacent thereto moving in the same direction therewith for controlling the feed of the magazines 80 and a releaser associated with said rotary device and an adjustable stop carried thereby, substantially as described.

7. In combination with the feed drum, a toothed wheel opposite the peripheral surface of the drum, a releaser to shield more or less of the teeth of said wheel from the sheets to be fed, and means for adjusting the size of the space between said releaser and the surface of the feed drum, substantially as described.

In testimony whereof, I affix my signature in presence of two witnesses.

CHARLES OWENS.
